(57) CLAIM

The ornamental design for a personal care bottle, as shown and described.

DESCRIPTION

FIG. 1 is a perspective view of a personal care bottle of the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings showing the bottom surface of the personal care bottle illustrate the portions of the design that form no part of the claim.
